UNITED STATES PATENT OFFICE

2,655,200

RECLINING ARTICLE OF FURNITURE

Anton Lorenz, Buffalo, N. Y.

Application October 16, 1946, Serial No. 703,559

12 Claims. (Cl. 155—105)

1

The present invention relates to articles of furniture, and more particularly to a reclining article of furniture, wherein the seat and the back-rest form movable links of a polygonal compound linkage including a sliding pair.

An object of the present invention is to provide a reclining article of furniture of above described type, wherein the movable members of the article of furniture are very well balanced, so that an occupant resting in the article of furniture may bring the movable members of the article of furniture from one position into another position without great effort.

A further object of the present invention is to improve upon reclining articles of furniture as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining chair according to the invention, a portion of a side wall of the support being broken away,

Fig. 2 is a fragmentary side elevational view, partly in section, of the arm rest of the chair shown in Fig. 1, in an enlarged scale,

Fig. 3 is a sectional view taken on line 3—3 of Fig. 1,

Fig. 4 is a side elevational view of a further embodiment of an adjustable reclining chair according to the invention, a portion of a side wall of the support being broken away,

Fig. 5 is a side elevational view, partly in section, of the arm rest of the chair shown in Fig. 4, in an enlarged scale,

Fig. 6 is a sectional view taken on line 6—6 of Fig. 5,

Fig. 7 is a sectional view taken on line 7—7 of Fig. 5,

Fig. 8 is a side elevational view of another embodiment of an adjustable reclining chair according to the invention, a portion of a side wall of the support being broken away,

Fig. 9 is a side elevational view, partly in section, of the arm-rest of the chair shown in Fig. 8, in an enlarged scale, and

Fig. 10 is a sectional view taken on line 10—10 of Fig. 9.

Referring now to Figs. 1—3, 220 generally indicates a rigid support comprising two side frames

2

222 rigidly connected with each other by transverse rods 200 and 224. The adjustable reclining chair shown in said figure has a permanently constrained linkage including the back-rest 236, the seat 244, the front link 260, the top link or arm-rest 262 and the guiding link 290 as movable links and the portion of the support 220 between the pivot 252 of the back-rest 236 and the pivot 296 of the guiding link 290 as a stationary link.

As best shown in Figs. 1 and 2, the top link 262 has a hollow portion with a slot 272 for the passage of the front link 260 and the guiding link 290, a great portion of which is concealed by the walls of the hollow portion of the top link 262.

A guiding means or guiding rod 282 secured to the top link 262 is arranged within said hollow portion of the top link 262. The upper portion 293 of the guiding link 290 embracing the guiding rod 282 forms the slider of the sliding pair 293, 282 of the polygonal link-system of the chair. The slider 293 may be displaced relative to the guiding rod 282 between the set collars 271 and 278 secured to the guiding rod 282. The lower end portion of the guiding link 290 is pivoted to the support 220 at 296.

The rear portion of the top link 262 is pivoted at 288 to an intermediate point of the back-rest 236 in a plane above the plane of the seat 244. The lower end portion of the back-rest 236 is pivotally connected with the rear portion of the seat 244 at 252. The front portion of the seat 244 is pivoted at 256 to the lower end portion of the front link 260, the upper end portion of which passing through a slot 218 of the guiding rod 282 is pivoted to the latter at 264. Thus, the pivotally connected back-rest 236, seat 244, front link 260 and top link 262 form a four-sided link-system of a polygonal linkage including the swingable guiding link 290 shiftably engaged with the guiding rod 282 of the top link 262. The four-sided link-system 236, 244, 260, 262 is swingably mounted on the support 220 at 252 in co-axial alignment with the pivotal connection between the back-rest 236 and the seat 244 at a point spaced from the pivotal connection 296 between the support 220 and the guiding link 290.

When the back-rest is swung about its pivot 252, the movable members of the chair may be brought, for example, from the sitting position shown in full lines, into a reclined position, for example, the extreme reclined position shown in dash-and-dot lines.

The sitting position is limited by an abutment of the seat 244 against the cross-bar 200 acting as a stop. The extreme reclined position is limit-

ed by an abutment of the set-collar 278 secured to the guiding rod 282 against the guiding link 290.

The movable members of the chair may be held in any desired position by means of a locking device generally indicated by 221. As best shown in Figs. 1 and 2, the connecting link 290 is in the shape of a clip having bores 223 for rotatable engagement with the bolt 296 mounted on the side wall 222 of the support 220. A square portion 225 of the bolt 296 is inserted into a corresponding square aperture of the side wall 222 of the support 220. A head 227 of the bolt 296 rests against a surface of said side wall 222. The square portion 225 prevents the bolt 296 from rotation when a locking knob 229 is screwed on the threaded end of the bolt 296. When said locking knob 229 is loosened, the guiding rod 282 may freely slide in the clip 290, so that the members of the chair may be moved from one position into another one. When the locking knob 229 is tightened, the clip 290 is tightened on the guiding rod 282 whereby the latter and the movable members of the chair are held in their position. Of course, any other suitable locking device may be used for locking the movable members of the chair in a predetermined position, if desired.

The adjustable reclining chair shown in Fig. 4 comprises a support 320 including side walls 322 connected with each other by cross-bars 300 and 324.

The top link generally indicated by 362 comprises a solid front portion 331, a hollow intermediate portion 333 and a solid rear portion 335. As best shown in Figs. 5 and 7, the intermediate portion 333 is rigidly connected with the front portion and the rear portion 335 by screws 337 or the like. The intermediate portion 333 has a slot 312 for the passage of a connecting link 390 swingably mounted on the support 320 at 396. A slider or sliding block 393 rigidly secured to the upper end portion of the guiding link 390 by means of screws 339 is slidably engaged with a guiding surface 341 formed by a portion of the inner surface of the hollow intermediate portion 333 of the top link 362.

The rear portion 335 of the top link 362 is pivoted to an intermediate point of the back-rest 336 at 388. The lower end portion of the back-rest 336 is pivoted to the rear portion of the seat 344 at 352. The front portion of the seat 344 is pivoted at 356 to the lower portion of the front link 360, the upper portion of which is pivoted to the front portion 331 of the top link 362 at 364. Thus, the pivotally interconnected back-rest 336, seat 344, front link 360 and top link 362 form a four-sided link-system of a polygonal linkage including the guiding link 390 and the sliding pair 341, 393. The seat 344 being a member of said four-sided link-system is pivoted at 343 to the support at a point spaced from the pivotal connection 352 between the back-rest 336 and the seat 344 and, furthermore, spaced from the pivotal connection 356 between the support 320 and the guiding link 390. The linkage of the chair shown in Fig. 4 is permanently constrained.

On each side of the chair, the front link 360 forms an upward extension of a leg-rest 354. Of course, if desired, the leg-rest 354 could be made of a separate piece of material rigidly connected with the front links 360 in any desired manner.

The sitting position of the movable members of the chair shown in full lines is limited by the

cross-bar 300 on which the seat 344 comes to a rest. The extreme reclined position of the movable members of the chair shown in dash-and-dot lines is limited by an abutment of the surface 345 of the front portion 331 of the top link 362 against the slider 393.

The movable members of the chair may be held in any desired position, for example, in the extreme reclined position or in any other intermediate position by means of a locking device generally indicated by 347 and arranged on the pivot 388 connecting the rear portion 335 of the top link 362 with the back-rest 336. As best shown in Figs. 4, 5, 6, said locking device 347 comprises a handle 349 screwed on the threaded end of the pivot 388. Said pivot 388 has a head 351 resting against the surface of the back-rest 336. A square portion 353 of the pivot 388 is inserted into a corresponding square aperture of the back-rest 336, whereby the pivot 388 is prevented from rotation when the locking handle 349 is turned. When the user of the chair loosens the locking handle 349, the surface of the hub 355 of said handle is disengaged from the surface of the rear portion 335 of the top link 362, so that the movable members of the chair may be freely moved from one position into another one. When the locking handle 349 is tightened, the surface of the hub of the handle is pressed against the rear portion 335 of the top link 362, whereby the latter is pressed against the back-rest 336 engaged with the head 351 of the pivot 388, so that the members of the chair are held in their position. Of course, any other type of locking device may be used instead of said locking device 347, if desired.

According to the embodiment of an adjustable reclining chair shown in Fig. 8, the support 420 comprises the side walls 424 connected with each other by cross-bars 400 and 424.

The top link generally indicated by 462 comprises a main portion 451 and an extension 459 integral with each other. Said extension 459 includes a hollow portion, wherein the guiding rod 482 is mounted. A hook-like member 461 having a threaded upper end is screwed into a threaded bore of said guiding rod 482.

The rear end of the main portion 451 of the top link is pivoted to an intermediate point of the back-rest 436 at 488. The lower end of the back-rest 436 is pivoted to the rear portion of the seat 444 at 452. The front portion of the seat 444 is pivoted to the lower end portion of the front link 460 at 456. The upper end portion of said front link 460 is swingably mounted on the end 463 of the hook-like member 461 in a plane somewhat below the plane of the longitudinal axis of the top link 462. The lower end portion of the guiding link 490 being in the shape of a clip is swingably mounted on the support 420 at 496. The upper end portion 493 of the guiding link 490 embracing the guiding rod 482 is slidably engaged with said guiding rod 482 arranged in the forward extension 459 of the top link 462 projecting beyond the pivotal connection 463 between the front link 460 and the top link 462.

The polygonal linkage of the chair comprises the four-sided link-system 436, 444, 460, 462 swingably mounted on the support 420 at 452, the guiding link 490 and the sliding pair 493, 482.

The movable members of the chair may be held in any desired position by means of a locking device generally indicated by 421 and arranged on the pivot 496.

The sitting position of the movable members

of the chair shown in full lines is limited by the cross-bar 400 on which the seat 444 comes to a rest, and the extreme reclined position of the movable members of the chair shown in dash-and-dot lines is limited by an abutment of the set-collar 478 against the guiding link 490.

I have described preferred embodiments of my invention, but it is understood that this disclosure is for the purpose of illustration, and that various omissions, or changes in shape, proportion, and arrangement of parts as well as the substitution of equivalent elements for the elements shown and described may be made without departing from the spirit and scope of the invention as set forth in the appended claims.

For example, the guiding rod slidably engaged with the slider mounted on the guiding link must not necessarily be arranged within a hollow portion of the top link; the guiding rod could also be arranged outside the top link proper.

Furthermore, the guiding rod may be omitted entirely, and the slider may embrace a guiding surface of the body of the top link proper.

Moreover, the invention may be applied to other articles of furniture than the type of chairs shown in the drawings, for example, to office chairs, chairs for use in railroad cars, chairs for use in airplanes, loungers, etc.

What I claim is:

1. An article of repose for supporting the body of a person, comprising in combination: a rigid support, a permanently constrained linkage having stationary link-means and a plurality of movable links, said stationary link-means being included in said support, said movable links including a seat-member, a back-rest-member, a guiding link, a top link and a front link, said front link being pivoted at a first point to the front end portion of said seat-member and being pivoted at a second point, spaced from said first point, to the front end portion of said top link, the rear end portion of said top link being pivoted to said back-rest-member, means pivotally connecting at least one of said back-rest- and seat-members with said support, one end portion of said guiding link pivoted to said support, and an elongated slidable connection between the other end portion of said guiding link and said top link.

2. In an article of repose as claimed in claim 1, said slidable connection including guiding means arranged on said top link, and an elongated slider mounted at said other end portion of said guiding link and slidably engaged with said guiding means.

3. In an article of repose as claimed in claim 1, at least a portion of said top link being hollow and having a slot, said slidable connection including guiding means arranged within said hollow portion of the top link, and an elongated slider mounted at said other end portion of said guiding link and slidably engaged with said guiding means, and said other end portion of the guiding link passing through said slot into said hollow portion of the top link.

4. In an article of repose as claimed in claim 1, said slidable connection including a guiding surface arranged on said top link, and an elongated slider mounted at said other end portion of said guiding link and slidably engaged with said guiding surface.

5. In an article of repose as claimed in claim 1, at least a portion of said top link being hollow and having a slot, said slidable connection including a guiding surface arranged within said

hollow portion of the top link, and an elongated slider mounted at said other end portion of said guiding link and slidably engaged with said guiding surface and said other end portion of the guiding link passing through said slot into said hollow portion of the top link.

6. In an article of repose as claimed in claim 1, said slidable connection including guiding means arranged on said top link, and an elongated slider mounted at said other end portion of said guiding link and slidably engaged with said guiding means, and stop means mounted on said top link for cooperation with said slider so as to limit at least one extreme position of the movable links

15 of the constrained linkage.

7. In combination with an article of repose as claimed in claim 1, a leg-rest swingably mounted on the front portion of the seat, and a member of said constrained linkage being operatively connected with said leg rest for controlling the movements of the latter.

8. An article of repose for supporting the body of a person, comprising in combination: a rigid support, a permanently constrained linkage having stationary link-means and a plurality of movable links, said stationary link-means being included in said support, said movable links including a seat-member, a back-rest-member, a guiding link, a top link and a front link, said back-rest-member being in pivoted connection with the rear end portion of said seat-member, said front link being pivoted at a first point to the front end portion of said seat-member and being pivoted at a second point, spaced from said first point, to the front end portion of said top link, the rear end portion of said top link being pivoted to said back-rest-member at a point spaced from the pivotal connection between the back-rest-member and the seat-member, at least one of said back-rest- and seat-members being pivotally connected with said support, one end portion of said guiding link being pivoted to said support, and an elongated slidable connection between the other end portion of said guiding link and said top link.

9. In an article of repose as claimed in claim 8, said seat-member being pivoted to said support at a point being spaced from the pivotal connection between said seat-member and said back-rest member.

10. An article of repose for supporting the body of a person, comprising in combination: a rigid support, a permanently constrained linkage having stationary link-means and a plurality of movable links, said stationary link-means being included in said support, said movable links including a seat-member, a back-rest member, a guiding link, a top link and a front link, said front link being pivoted at a first point to the front end portion of said seat-member and being pivoted at a second point, spaced from said first point, to said top link, the rear end portion of said top link being pivoted to said back-rest member, and means pivotally connecting at least one of said back-rest- and seat-members with said support, said top link having a forward extension projecting beyond its pivotal connection with the front link, one end of said guiding link being pivoted to said support, and the other end of said guiding link being shiftably engaged with said forward extension of the top link.

11. An article of repose for supporting the body of a person, comprising in combination: a rigid support, a permanently constrained link-

age having stationary link-means and a plurality of movable links, said stationary link-means being included in said support, said movable links including a seat-member, a back-rest member, a guiding link, a top link and a front link, a guiding rod rigid with said top link, said front link being pivoted at a first point to said seat-member and being pivoted at a second point, spaced from said first point, to the front end portion of said top link, the rear end portion of said top link being pivoted to said back-rest member, means pivotally connecting at least one of said back-rest and seat-members with said support, one end of said guiding link being pivoted to said support, and a slider mounted on the other end of said guiding link and slidably engaged with said guiding rod.

12. An article of repose for supporting the body of a person, comprising in combination: a rigid support, a permanently constrained link- 20 age having stationary link-means and a plurality of movable links, said stationary link-means being included in said support, said movable links including a seat-member, a back-rest member, a guiding link, a top link and a front

5
10
15

link, a guiding rod rigid with said top link, said front link being pivoted at a first point to said seat-member and being pivoted at a second point, spaced from said first point, to said guiding rod, the rear end portion of said top link being pivoted to said back-rest member, means pivotally connecting at least one of said back-rest and seat-members with said support, one end of said guiding link being pivoted to said support, and a slider mounted on the other end of said guiding link and slidably engaged with said guiding rod.
